UNITED STATES PATENT OFFICE.

GEORGE SWIFT, OF MERIDEN, CONNECTICUT, ASSIGNOR TO THE AEOLIAN COMPANY, OF MERIDEN, CONNECTICUT, AND NEW YORK, N. Y., A CORPORATION OF CONNECTICUT.

PERFORATED MUSIC-SHEET FOR MECHANICAL MUSICAL INSTRUMENTS.

No. 837,517.

Specification of Letters Patent.

Patented Dec. 4, 1906.

Application filed March 9, 1900. Serial No. 8,052.

To all whom it may concern:

Be it known that I, GEORGE SWIFT, a citizen of the United States, and a resident of Meriden, in the State of Connecticut, have 5 invented certain new and useful Improvements in Perforated Music-Sheets for Mechanical Musical Instruments, of which the following is a specification accompanied by drawings.

10 The invention relates to perforated music-sheets for controlling "pianolas" and other makes of mechanical apparatus for playing pianofortes, whether such apparatus is built into the musical instrument or is portable 15 and separate therefrom. These instruments, as well understood, have pneumatic tracker-boards, and the music-sheets are pneumatic-valve-sheets which control said tracker-boards. The invention is applicable particu- 20 larly to such mechanism. Its object is to render the operation of such apparatus less mechanical in effect and more like perfect manual playing.

25 Mechanical musical apparatus controlled by perforated music-sheets were known and used for many decades prior to this invention, and there has been a continuing effort among the builders and designers of such apparatus to simulate more closely perfect 30 manual playing and to remove or ameliorate the mechanical sound which this class of music has so far had despite all efforts of those engaged in improving such apparatus. Prior to this invention pneumatically-oper- 35 ated players had reached a certain stage of progress by which the noises of the mechanism were greatly reduced and the softness of the human touch closely simulated. Fur- 40 thermore, the introduction of the tempo-controller for varying the tempo at the will of the player and of the expression-controller for varying the force of the blows at will to produce effects ranging from pianissimo to fortissimo in accordance with the pleasure 45 and musical feeling of the player, combined with the use of the loud-pedal for sostenuto and other appropriate effects, seemed to many in this art to have endowed the appa- 50 ratus with about all the properties that hu- man ingenuity could create, with the possi- ble exception of same means for accentuating individual notes or parts. Even these lat- ter, indeed, in several different forms had

been devised. It seemed, therefore, to those most familiar with the art that little more re- 55 mained to do, provided equal thoroughness and care were devoted to the preparation of the perforated music-rolls in a perfect and exact accordance with the musical score of the composition to be played. This was 60 done in many instances with greatest care and expense, and a seemingly perfect perforated sheet was obtained when the lengths of the several note-perforations and their pos- 65 tions and sequence were in perfect propor- 70 tion and correspondence with the directions of the composer. Thus, for example, if an eighth-note was perforated one-quarter of an inch in length a quarter-note would be one-half inch in length and a whole note two 75 inches in length. As early as the year 1881 this rule was clearly enunciated in a United States patent granted to one Schmoele, and it was carefully followed for more than a decade thereafter, the mechanical-musical-in- 80 strument makers asserting that these instru- 85 ments played more accurately than the ma- jority of pianists, but the musicians, on the other hand, complaining that the very sound of the music indicated its mechanical origin. 90

The object of the present invention was to meet this criticism and to improve, if it were indeed possible, that which many in the me- 95 chanic art insisted was already mathemati- cally and scientifically perfect and which from their point of view was only criticised by the prejudice of the musicians.

My discovery which, following on long ex- 95 periment, produced my present invention was as follows: The prolongation of the sev- 100 eral note-perforations of the legato melody in any particular part of the composition or in all legato parts of the composition produces a smoothness of sound and melodiousness without any such dissonances as might be inferred from the resulting overlapping of 105 succeeding note-perforations. This pro- longation or increment in the perforation has, so far as I have been able to discover, no ra- tional or proportional relation to the length 110 of the corresponding note. The increment may be the same absolute amount for a six-teenth-note as for a whole note. By this simple difference the defect in the music otherwise produced is at once both elimi- 115 nated and also demonstrated. The reality

of the problem, the very existence of which was so long disputed between the musicians and the musical-machine makers, thus was proved by its very solution.

5 In the following description I employ the terms "non-legato" and "mezzo staccato" to mean the playing of notes in musical sequence in the same part or melody in a manner in which the sound of one note ceases 10 somewhat before the sounding of the succeeding note commences. By "staccato" I mean a manner in which the sound of one note not only ceases before the succeeding note, but is also made of extremely short duration absolutely as well as relatively. By 15 "legato" I mean smooth playing in a manner in which in its most perfect form the sound of one note continues to and until the sounding of the succeeding note with no interruption, but does not overlap in duration, 20 because such simultaneous sounding of two succeeding notes not in accord should produce an objectionable and painful blurring and dissonance. The most perfect example 25 and at the same time demonstration of this fact is found in perfect legato singing, where- 30 in the larynx is not closed at any time, and the note changes without interruption, on the one hand, and without possible overlapping, on the other hand, because there is mani- 35 festly only one note-sounding organ or larynx at work.

In carrying out the present invention, 35 where the musical score indicates staccato, the shortest perforation of the entire perforated roll may be employed. For legato (indicated by the score where no markings or where slurs appear) the perforations are not to terminate one where the next commences, to correspond to the sounds as exemplified above by the human voice, but, on the contrary, are to be prolonged, and therefore overlapped considerably, by a small increment of length just as though a blurred 40 or dissonant effect were to be expected. I know of no musical notation which would correspond with or indicate any such overlapping of the musical tones themselves, and as the effect produced by a sheet so perforated simulates the most perfect legato- 45 playing without any blurring or dissonance it is not conceivable that it really occurs to any appreciable extent in the music produced. The amount of such prolongation, overlap, or 50 increment may be, as will be shown in the accompanying drawings, more than the entire length of a sixteenth-note without increment. The increment may be a fixed amount. Thus the perforation for such a short note 55 may be doubled in length, so that, for example, the first one of three such notes shall not terminate till the third commences. Such increment or prolongation when applied to a whole note is by itself hardly 60 noticeable to the eye. I have not, therefore,

discovered that the increment or overlap is in any way affected by the length of the musical note, whether a sixteenth, quarter, or whole note, nor yet by the number of notes in a given measure, whether thirty- 70 two thirty-second notes or but a single whole note. The increment or prolongation may be represented by a constant length, such as one-eighth of an inch for all portions of the melody or harmony to which it is desired to apply it at a given tempo or speed of the mechanism, and since my said discovery it is at once demonstrable in the following manner that such increment or prolongation should to obtain the best results vary in respect to the tempo of the movement being rendered, though the reason why was not for a long time clear to me. If a sheet constructed in accordance with this invention is stopped, so that the overlapping end of one perforation leaves the tracker-duct open at the same time that a succeeding perforation differing by only a semitone leaves its duct open, then by opening and closing the two ducts with the finger-tips it at once becomes apparent that the simultaneous sounding of the two notes produces dissonance, and therefore for music-sheets having very slow movement of the paper the overlap should be relatively shorter than for music-sheets in 90 which the movement of the paper is rapid. In order to strikingly distinguish the manner in which I vary the perforations under the present invention for different musical notes, let the letter L represent the fraction of a musical measure proportional to a normal or legato eighth-note. Then twice L will represent the fraction of the musical measure for a quarter-note, and four times L a half-note, and eight times L a whole note. Now 100 let the same signs designate the exactly proportionate lengths and fractions of lengths allotted to each measure on the perforated music-sheet, and let i be my increment for prolonging the perforations. Prior to my 105 invention the proper perforation lengths were supposed to be perfectly attained by studied and careful representation of the exact lengths of the notes and measures to correspond—e. g., Schmoele patent, No. 115 237,208, of 1881—that is to say, a normal or legato sixteenth-note, one-half L; a normal or legato eighth-note, length L; a normal or legato quarter-note, 2 L; a normal or legato half-note, 4 L; a normal or legato whole note, 8 L; a dotted quarter-note, 3 L, &c. Now introducing my invention of the increment or prolongation for legato notes on the pianoforte, the following entirely new relations, which are no longer proportionate and 120 which are at variation with the score, are produced: A normal or legato sixteenth-note, one-half L plus i ; a normal or legato eighth-note, L plus i ; a normal or legato quarter-note, 2 L plus i ; a normal or legato 125 quarter-note, 4 L plus i ; a normal or legato 130 quarter-note, 8 L plus i ; a dotted quarter-note, 3 L plus i , &c.

half-note, 4 L plus *i*; a normal or legato whole note, 8 L plus *i*; a dotted quarter-note, 3 L plus *i*, &c. Thus it will be seen that my increment or prolongation *i* is not 5 a quantity contemplated by a composer or shown in the musical score, nor is there any musical notation that can show it, but it has relation to causes or effects not so far capable of ascertainment and proof. As will be 10 presently seen from the accompanying drawings, the amount of overlap *i* may equal or exceed the length one-half L of an unprolonged sixteenth-note. This overlapping, prolongation, or increment is applicable to all notes 15 in a composition, except to staccato and mezzo-staccato notes and the ends of phrases.

In the drawings, Figure 1 represents a few measures of a musical score in D-flat, Chopin's *Berceuse*, in which the tempo is one hundred 20 eighth-notes to the minute. Fig. 2 shows a corresponding portion of a perforated music-sheet in which the perforations are of length to correspond carefully with the duration of the sound indicated by the score. Fig. 3 is 25 a scale marked with the corresponding musical letters and placed in line with the perforated sheet shown in Fig. 2 to indicate, in connection with Fig. 2, the musical notes corresponding with the note-perforations. 30 Fig. 4 represents a portion of a perforated music-sheet for the same musical composition as shown in Figs. 1 and 2, but embodying the present invention and showing the disproportionate lengths of the musical perforations as compared with the duration of 35 the musical notes in legato playing. Fig. 5 is a scale like Fig. 3. Figs. 6 and 7 are views corresponding with Figs. 2 and 3, showing an arpeggio or broken chord with perforations for playing it staccato at *b* and sustained at *d*.

In the drawings, A, Fig. 2, designates a perforated music-sheet having the usual perforations B therein. These perforations are 45 made and arranged in accordance with the musical composition represented in Fig. 1, being arranged in measures C, formed by bars D, to correspond, respectively, with the measures E and bars F of Fig. 1, the fine 50 cross-lines G of the sheet A representing the beats in each measure, corresponding in tempo to the beats shown in Fig. 1, the music being in six-eighths time. The lengths of the perforations B in Fig. 2 correspond 55 with the time of their respective notes in the music-sheet, Fig. 1. Thus, *e. g.*, the note H in Fig. 1 is an eighth-note, and its corresponding perforation J, Fig. 2, is of the length corresponding to one beat of the measure—*i. e.*, extending from a bar D to the next line G or from one line G to the next. In the same way in Fig. 1 M represents a quarter-note, and the corresponding perforation N in Fig. 2 extends from one line G 60 to the second succeeding line, which may be

a line G or bar D. The note R in the last measure, Fig. 1, is a dotted quarter-note equal to three-eighths notes, and the corresponding perforation S in Fig. 2 covers three beats of the measure, or three of the spaces 70 between the line D and a line G, or between two lines G. So, also, the sixteenth-note U, Fig. 1, has a corresponding perforation V, Fig. 2, which is equal to half the distance between two adjacent lines G. In the fifth and 75 sixth measures are several series of triplet sixteenth-notes, and as these are triplets the respective perforations in Fig. 2 are each made to cover one-third of the distance between two adjacent lines G. 80

By comparison of Fig. 2 with Fig. 1 it will be seen that the lengths of the perforations are proportioned to the duration of the musical sounds in perfect legato, and therefore Fig. 2 shows the carefully-constructed perforated note-sheet as it was constructed for piano as well as organ to correspond with a music-score, as shown in Fig. 1, before my discovery and invention. Sometimes there was a slight incidental and negligible excess 90 or overlap, as mentioned below, which is not shown in Fig. 2. Fig. 4 shows the increment or prolongation of perforations beyond the appropriate length that corresponds with the musical score, and this is particularly 95 noticeable in the treble. For example, in the first and second measures of the treble the successive notes are not in accord and would produce discord if sounded simultaneously. In some of the succeeding measures it will be 100 seen that the notes in the treble correspond with notes of a chord in one or two instances, and here the prolongation may be made excessive without harm. As the music shown in Fig. 1 is six-eighths time and as the lines 105 extending across the sheet in Fig. 4 leave intervals that correspond, therefore with one-eighth note equaling one-sixth of the length of each measure, it will be plainly seen that the treble-notes in the first measure, consisting of an eighth-note and several sixteenth-notes, appear in the perforated sheet in Fig. 4 as prolonged, as at *a*, by nearly equal amounts, and therefore by an amount which is not proportional to the different lengths of 110 notes. Thus the eighth-note is prolonged by an increment equal to one-quarter of its length, while the sixteenth-notes are prolonged about one-half beyond their appropriate length. The somewhat similar melody 115 in the treble of the second bar shows the sixteenth-notes prolonged to more than double their appropriate length. Indeed, two of them slightly exceed the length allotted to an eighth-note, and at least exceed the duration allowed to an eighth-note in perfect legato playing or singing. Nevertheless 120 when these perforated note-sheets are used no discordant overlapping appears in the music produced. 125 130

The prolongation of the triplet sixteenth-notes of the fifth and sixth measures is indicated at P in Fig. 4.

In order to prevent the possibility of confusion of my legato improvement with the effect of the loud pedal or the sostenuto prolongation of a note in accord with others, I call attention to the bass notes marked "Ped." in Fig. 1, and to the prolongation of these notes in Fig. 4, and particularly the notes K, to three times their appropriate length. This other matter forms the subject of a divisible application, and is now claimed herein.

The last notes in the bass of each of the measures shown are perforated exactly the same length both in Fig. 2 and Fig. 4, because being in parts of the accompaniment that are to be sustained for a third of the measure the increment which forms my invention is comparatively unimportant or negligible. Fig. 6 at d shows a broken chord played sostenuto. This, as just explained, must not be confused with the legato playing of successive notes that do not accord. The prolongation of the perforations in Fig. 6 at d of course represents the intentional prolongation of the musical sounds forming a chord. So far as I have been able to discover the increment or prolongation is of greater importance and advantage in the shorter legato notes. Measured in inches, and understanding that the drawings accompanying this application are somewhat less than one-half scale, the increment illustrated varies from about one-tenth of an inch in the first bar to a very much greater extent in the second bar, and I have so far preferred to use in practice an increment of about three-twentieths of an inch, or measured in terms of the width of the perforations shown, which I have usually made with a round punch. The preferred increment somewhat exceeds the width of the perforation, so that the full width of one perforation reaches in the legato notes to the full width of the succeeding perforation. Expressed in musical time, the preferred increment may with advantage in music of moderate tempo, like Chopin's Berceuse, illustrated in the drawings, exceed an unprolonged thirty-second note, and I have frequently, as shown in the second bar of Fig. 4, made it equal to about one unprolonged sixteenth note without objectionable dissonance. It is better in the present invention to err on the side of prolonging the notes in harmony until musical sounds produced certainly overlap than to risk the production of a mechanical sound in the playing.

Comparing now the increment or prolongation of the note-perforations in Fig. 4 and Fig. 2 and selecting the treble as the better illustration, because the melody is in the treble, the characteristic increment of the present invention will be readily seen. It is a curious

but easily-demonstrated fact that the note-sheet of Fig. 2, which is carefully perforated legato in correspondence with the duration of each note in the music without interruption until the commencement of the succeeding note and without overlapping, does not in practice produce the desirable non-mechanical effect that my improvement produces, while, on the other hand, my improved sheet, (shown in Fig. 4,) with its overlapped or prolonged perforations corresponding with successive notes in the melody that are not in accord or in harmony produces a highly-pleasing effect without any dissonance, jarring, or blurring.

I am aware that patent to Schmoele, No. 237,208, explains that the proper length of note-perforations is perfectly obtained on the musical sheet by a studied and careful representation of the exact length of notes and measures to correspond. My invention is the reverse of this in that the length of the note-perforations is increased in a manner which does not correspond with the music that is to be produced or with the musical score, and I make no claim whatever to music-sheets wherein the note-perforations are of the exact length of the notes and measures to correspond with the indications of the musical score.

I am also aware that long prior to my invention certain old automatic piano-playing machines controlled by perforated music-sheets were known and that the sheets necessarily had perforations prolonged and overlapped to permit coöperation with mechanical fingers, which had to pass into and out of such perforations, and which necessarily occupied a certain area of the perforations in their motions and operation, without, however, producing the results of the present invention—to wit, legato music. I only claim as my inventions my novel means as operative to produce and capable of being used to produce legato.

I am also at present well aware that in aeolian-grand music arranged by myself and others prior to my present discovery and invention there was an incidental or accidental overlap of about five one-hundredths of one inch, which resulted from the use of punch diameters which had to be greater than the feed or distance between centers of successive punch-perforations in order to make continuous note-perforations without ragged edges; but such overlap was negligible even in organ music and was neither an effective cause nor an operative cause of legato playing on aeolian grand or on pianola or any other instrument with which these sheets could be used.

I desire to secure by Letters Patent as novel and characteristic features of the invention the following:

1. A perforated music-sheet for control-

ling a mechanism for playing pianofortes, in which substantially all the note-perforations are prolonged at their rear ends beyond standards of length proportionate to the time value of the musical notes and are so arranged on the sheet that perforations in musical succession are overlapped by the amount of such prolongation or increment, whereby the said prolongations produce legato effect, for substantially the purposes set forth.

2. A perforated music-sheet for controlling a mechanism for playing pianofortes, having substantially all the legato-note perforations of the treble prolonged in the melody or air at their rear ends beyond the standards of length proportional to the appropriate time value of the musical notes and having note-perforations that are in immediate musical succession in parts or melodies that are not to be played non-legato overlapped lengthwise by the amount of such prolongation, whereby the sound of the music so mechanically produced is improved and the said prolongations produce legato effect, substantially as set forth.

3. A perforated music-sheet for controlling a mechanism for playing pianofortes, in which substantially all the legato-note perforations are prolonged at their rear ends beyond standards of length proportionate to the time value of the musical notes and are so arranged on the sheet that perforations in musical succession are overlapped by the amount of such prolongation or increment, the length of said prolongation or increment for succeeding notes that do not harmonize being substantially identical for quarter, eighth, sixteenth, and thirty-second notes, whereby said prolongation produces legato effect, substantially as set forth.

4. A perforated music-sheet for controlling a mechanism for playing pianofortes, in which substantially all the legato-note perforations in the treble are prolonged at their rear ends beyond the lengths proportional to the appropriate time value of the musical notes, said note-perforations that are in immediate musical succession in parts or melodies that are not non-legato, being overlapped lengthwise by the amount of such prolongation, said prolongation or overlap being substantially as great or greater than the shortest note-perforation, for substantially the purposes set forth.

5. A perforated music-sheet consisting of a sheet of material adapted for the pneumatic control of "pianolas" and other piano-playing mechanism, said sheet having substantially all the note-perforations excepting those designed for non-legato notes prolonged at their rear end beyond the standards of length adopted for the time value of notes or proportionate to the musical score, and having note-perforations that are in im-

mediate musical succession overlapped by the amount of such prolongation to a substantial extent as described, whereby the legato effect is produced in the pianoforte music.

6. As a new article of manufacture, a perforated music-sheet for producing legato playing of "pianolas" and similar mechanisms for playing pianofortes, the perforations of which have legato-producing prolongations which overlap the succeeding note-perforations throughout substantially all the legato passages of the composition, substantially as described.

7. A perforated pneumatic-valve sheet adapted to "pianolas" and similar apparatus having pneumatic trackers and for playing pianoforte music, said sheet having the perforations of legato-melody notes extended at their rear ends beyond the proportionate length corresponding to the score by a substantial increment, and the succeeding perforations overlapped not less than one-tenth of an inch, whereby a legato effect is produced in the pianoforte music, substantially as set forth.

8. A perforated pneumatic-valve sheet adapted to "pianolas" and similar apparatus having pneumatic trackers and for playing pianoforte music, said sheet having the perforations of legato-melody notes extended at their rear ends beyond the proportionate length corresponding to the score by a substantial increment, and the succeeding perforation overlapped to an extent equaling approximately the full width of the perforations, whereby a legato effect is produced in the pianoforte music, substantially as set forth.

9. A perforated pneumatic-valve sheet adapted to "pianolas" and similar apparatus having pneumatic trackers and for playing pianoforte music, said sheet having the perforations of legato-melody notes extended at their rear ends beyond the proportionate length corresponding to the score by a substantial increment, and the succeeding perforations overlapped not less than the length of an unprolonged thirty-second note, whereby a legato effect is produced in the pianoforte music, substantially as set forth.

10. A perforated pneumatic-valve sheet adapted to coöperate with the pneumatic tracker of "pianolas" and similar mechanism for playing pianofortes, said sheet having round-ended perforations and having the perforations of legato notes prolonged beyond the length proportionate to the score to an extent sufficient to bring the full width of such note-perforations at least beyond the round end portions at the commencement of the succeeding notes, whereby legato pianoforte music may be produced, substantially as set forth.

11. A perforated pneumatic-valve sheet

adapted to coöperate with the pneumatic trackers of "pianolas" and similar mechanism for playing pianofortes, said sheet having round-ended perforations and having the 5 perforations of legato notes prolonged beyond the length proportionate to the score to an extent sufficient to bring the full width of such note-perforations beyond the commencement of the succeeding notes and to 10 overlap the succeeding perforations by an amount exceeding the full width of the perforations.

12. A perforated pneumatic-valve sheet adapted to coöperate with the pneumatic

trackers of "pianolas" and similar mechanism for playing pianofortes, the perforations of the legato notes of which have legato-producing extensions which overlap the succeeding note-perforations substantially throughout all the legato passages of the composition, substantially as set forth. 15 20

In testimony whereof I have hereunto set my hand in the presence of two subscribing witnesses.

GEORGE SWIFT.
